DANIEL M. KAMPLER, OF NEW YORK, N. Y., ASSIGNOR OF FORTY-SEVEN AND ONE-HALF ONE-HUNDREDTHS TO JOSEF ROSENWASSER, OF NEW YORK, N. Y.

RESILIENT TIRE.

1,154,119.

Specification of Letters Patent. Patented Sept. 21, 1915.

Application filed April 2, 1915. Serial No. 18,647.

To all whom it may concern:

Be it known that I, DANIEL M. KAMPLER, a citizen of the United States, residing at New York city, county and State of New York, have invented a new and Improved Resilient Tire, of which the following is a specification.

This invention relates to a resilient tire of simple construction, which is adapted to sustain a heavy load and is not liable to become punctured or otherwise damaged during travel.

In the accompanying drawing: Figure 1 is a side view partly in section of a tire embodying my invention; Fig. 2 an enlarged cross section on line 2—2, Fig. 1, and Fig. 3 a plan of a portion of the tire.

The device consists essentially of an annular casing 10 composed of resilient sheet metal, and having a pair of thin convex sides. The casing is of a diameter to readily encompass the wheel felly 11 to which it is adapted to be secured by a pair of flanged clamp rings 12 or otherwise. The construction of the casing is such that its top and bottom are made integral with one of its sides, while the other side or cover 13 may be soldered or otherwise connected to the top and bottom. The top of the casing is provided with a plurality of apertures 14 for ventilating purposes.

Within casing 10 is contained a core composed of several windings of a heavy rope 15, the strands of which are formed of hemp and cotton. The rope is so laid as to form a row of inner coils, placed sidewise of each other, a row of intermediate coils encircling the inner coils, and a row of outer coils encircling the intermediate coils. In this way the rope windings will completely fill out the casing and form a resilient core that contacts with the inner walls thereof. The cotton constituent of the rope imparts to it a desirable degree of elasticity, while the hemp serves to add the necessary strength and consistency.

Around the casing, there is fitted an endless flexible strap 16 which is centered upon

the casing and is of less width than the latter, so that the casing projects to the right 50 and left of the strap. Over strap 16 there are fitted a number of spaced shoes 17 which are transversely corrugated as shown, and are of a width corresponding to that of the casing, so that they extend over the exposed 55 portions of the latter. Bolts 18 passing through the casing and shoes to the right and left of the strap, draw the shoes down at both sides into contact with the casing and thus serve to house the strap between casing 60 and shoes.

In assembling the parts, the casing is encompassed by strap 16, the shoes 17 are bolted to the casing, the latter is charged with the filling, and then the cover 13 is closed 65 and soldered in position.

It will be seen that the tire is of superior strength which well adapts it for sustaining heavy weights, and that it nevertheless possesses a high degree of resiliency. So also 70 the reinforcing strap 16 will be sustained in position by the laterally protruding portions of the shoes 17, and their direct connection with the casing, while furthermore by this construction the assemblage of the parts is 75 greatly facilitated.

I claim:

1. A tire comprising an annular sheet metal casing, means for securing said casing to a wheel rim, and a flexible filling within 80 the casing, said filling being composed of a plurality of rope-windings which are arranged in a series of overlying rows, that contact with the inner walls of the casing.

2. A tire comprising an annular sheet 85 metal casing, means for securing said casing to a wheel rim, and a flexible filling within the casing, said filling being formed of a coil of rope the strands of which are composed of hemp and cotton.

3. A tire comprising a casing, a strap surrounding the casing, a series of spaced shoes that project sidewise over the strap, and bolts connecting the shoes to the casing at both sides of the strap.

DANIEL M. KAMPLER.
